(57) **CLAIM**

The ornamental design for a proximal flow sensor, as shown
and described.

DESCRIPTION

FIG. 1 is a top perspective view of a proximal flow sensor;
FIG. 2 is a bottom perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof; and,
FIG. 9 is an environmental view thereof.
The broken lines illustrate portions of the proximal flow
sensor that form no part of the claimed design.
